UNITED STATES PATENT OFFICE.

JOHN BERG, OF CHICAGO, ILLINOIS, ASSIGNOR TO METAL SPECIALTIES MANUFACTURING COMPANY, OF CHICAGO, ILLINOIS, A CORPORATION OF ILLINOIS.

SEAL-MOISTENING MACHINE.

1,314,941.

Specification of Letters Patent.

Patented Sept. 2, 1919.

Application filed December 14, 1917. Serial No. 207,082.

To all whom it may concern:

Be it known that I, JOHN BERG, a citizen of the United States, residing at Chicago, in the county of Cook and State of Illinois, have invented a new and useful Improvement, 5 in Seal-Moistening Machines, of which the following is a specification.

This invention relates particularly to machines adapted for moistening gummed seals 10 and labels to enable the seals to be readily applied to a package or envelop.

The primary object is to provide an improved machine which is particularly well adapted to the purpose of moistening seals 15 of the character employed for securing parcel-post packages, or the like, where it is desirable to enable the contents of the package to be inspected by the postal authorities. Such a seal usually comprises two members, 20 each provided with a gummed surface, said members having interlocking connections of a character enabling the package to be held securely fastened, said members being, however, readily separated or detached from 25 each other to enable the contents of the package to be inspected.

The invention is illustrated in its preferred embodiment in the accompanying drawing, in which—

30 Figure 1 represents a plan view of a moistening machine embodying the invention, one of the presser-rolls employed being shown brokenly; Fig. 2, a vertical sectional view taken as indicated in line 2, Fig. 1; Fig. 3, a rear side view of the machine with the roll-shields and presser-rolls mounted thereon broken away; Fig. 4, an outer plan view of a two-part seal, the gummed surfaces of which may be moistened readily by 35 means of the improved machine; Fig. 5, an inner face view of said seal; and Fig. 6, a broken sectional view, showing a modification of the machine.

In the embodiment of the invention illustrated in Figs. 1—3, A represents a water-font which is supported by legs A¹; B, B, a pair of aligned moistening-rolls secured on a shaft B¹ having its ends journaled in the end walls of the water-font; C, C, a pair of 40 roll-shields disposed above the moistening-rolls B and supported upon the ends of the water-font; D, D, a pair of presser-rolls which rest upon the moistening-rolls B and are loosely mounted in suitable brackets carried by the members C; and E, a receptacle

or holder for seals, said holder being detachably connected with one side of the water-font and having a guide wall E¹ located between the holder and one side of the water-font.

60 The water-font A preferably comprises a trough-like body or half cylinder, supported at its ends by the legs A¹, as indicated, and having its end walls provided at their upper edges with bearings 1 for the ends of the shaft B¹. The moistening-rolls B, B, are preferably composed of porcelain, and fixed on the shaft B¹, being separated from each other by a space 2. In the illustration given, the rolls are provided with hubs 3, 70 but this feature is unimportant.

Each of the shields C preferably comprises a substantially horizontal sheet-metal member 4, whose outer end is provided with a downturned arm 4^a, which is secured to the 75 corresponding end wall of the font A, as by means of screws 5. Each shield C is provided with a longitudinal slot 6, enabling the presser-rolls D to extend therethrough and make contact with the moistening-rolls B, 80 upon which they rest.

The rolls D preferably are composed of metal, or glazed porcelain, and provided with short reduced extensions 7, which are supported in elongated or slotted bearings in 85 lugs or flanges 8 with which the shields are provided.

The body of each shield C comprises a substantially flat horizontal member, and the inner ends of said shields are separated by a 90 space corresponding with the space 2 between the moistening-rolls. The lateral edges of each shield C are curved upwardly, as indicated at 9 and 9^a in Fig. 2. The shield provides a surface 9^b which is spaced 95 slightly above the moistening-roll B; and the presser-roll D extends below the surface 9^b and rests upon the roll B.

The seal-holder E in the form illustrated, 100 comprises a receptacle 10 which is adapted to support a pack of seals F on edge, as may be understood from Fig. 2. The receptacle 10 may be formed of sheet-metal, bent into U-form to afford a channel or space 10^a in which the seals may be supported on edge. From the upper portion of the inner lateral wall of the holder 10, there extends the inclined guide-wall E¹ 105 over which the seal may be drawn by the thumb and finger as the ends of the seal 110

are passed between the moistening-rolls and superposed presser-rolls. The wall E^1 may be formed integrally with the inner wall of the receptacle 10, as illustrated in Fig. 5 2. Preferably, the wall or apron E^1 is provided at its upper edge with a hook or flange 11 which hooks over the upper edge of the adjacent wall of the water-font. In the illustration given, the metal of the apron 10 E^1 is incised to provide a central tongue 12 at the upper portion of the apron, which is bent downwardly, so that its edge will engage the outer surface of the wall of the water-font in the manner illustrated in Fig. 15 2. Thus, the integral seal-holder and apron is detachably secured to one side-wall of the water-font. Preferably, the receptacle 10 inclines outwardly and upwardly, as illustrated in Fig. 2. Also, by forcing the 20 tongue 12 downwardly to the position shown in Fig. 2, there is provided through the upper portion of the inclined apron E^1 a comparatively wide slot or space 12^a which is in transverse alinement with the space 25 2 between the moistening-rolls B. This facilitates the operation of drawing a seal up the inclined surface E^1 and between the moistening-rolls and presser-rolls, the thumb and finger passing through the space between the moistening-rolls. The shields C serve not only as supports for the presser-rolls D, but also as guides beneath which the gummed ends of the seal will pass. Between the flanges 9 and the upper portion 30 35 of the apron E^1 , there is afforded a throat 13 through which the end-portions of the seal pass on the way to the rolls.

It is desirable to provide the device E with yielding means for holding the seals 40 F in position. In the illustration given, there are provided two yielding fingers 14 which are adapted to engage the upper edges of the seals. Each of the fingers 14 preferably comprises a thin metal-bar which 45 is of springy character and of angular form. Each of said members has a shank 14^a which is adjustably connected with the outer wall of the receptacle 10. Said shanks are inclined, or convergent upwardly, so that the 50 edges of the fingers 14 will contact with the upper edges of the seals. Each shank 14^a is provided with a series of perforations 15, any one of which may engage a pin or stud 15^a carried by the outer wall of the 55 receptacle 10; and each shank 14^a is provided with a slot 16 which is engaged by a screw 17 extending therethrough and into the outer wall of the receptacle 10. The outer wall of the receptacle 10 may be cut 60 away, as indicated at 10^b, although this is a matter of small importance.

The machine is well adapted to the purpose of moistening the gummed surfaces of the two-part seal F, illustrated in Figs. 4 65 and 5. The seal illustrated comprises some-

what stiff paper strips 18 and 19, the strip 18 having a pair of slots 18^a, and the strip 19 having tongues 19^a detachably interlocked with the slots 18^a. The inner surfaces of said strips are gummed, as indicated at 18^b and 19^b.

A pack of the seals F may be inserted in the holder E, the lower longitudinal edges of the seals resting in the bottom of the receptacle and the upper longitudinal edges of the seals contacting with the yielding fingers 14, the gummed surfaces of the seals being turned toward the font A. Thus, the reinforced, interlocking central portions of the two-part seals will be so disposed that the interlocking portion of the seal may be grasped by the thumb and finger; and the operator, standing in front of the machine, will draw the seal upwardly over the inclined apron E^1 , through the throat 13 and between the moistening-rolls B and presser-rolls D. The guide-shields C insure the approximate proper passage of the seal in a horizontal position through the machine; and the presser-rolls cause 90 the gummed surfaces of the seal to bear against the upper surfaces of the moistening-rolls. As the seal is drawn through, the rolls are thereby rotated, it being understood that the lower portions of the moistening-rolls are immersed in water, so that moisture will be supplied to the gummed surfaces of the seals as they pass over the moistening-rolls.

The water-font may be readily cast in the 100 form illustrated; and the other elements of the device may be readily applied. It will be understood, therefore, that the machine is practically of knock-down construction; that it may be cheaply manufactured and 105 easily assembled; and that it is well adapted to the purpose of moistening two-part seals, such as are desirable for book post, parcel post, and wrappers and packages, generally, where it is necessary or desirable 110 to be able to undo the package and do it up again. The machine may be used for moistening labels, also.

In the modification shown in Fig. 6, A² represents the water-font; C¹, a shield or 115 presser-member, supported like the shields C and co-acting with the moistening roll B¹; and F¹, a seal or label being passed through the machine. In this case, the shield or presser-member C¹ is curved or bowed concentrically with the moistening-roll, and the presser-roll is dispensed with. The space between the member C¹ and roll B¹ is sufficiently constricted to cause the seal to be pressed against the roll about which it 120 is caused to curve, owing to the natural stiffness and resiliency of the seal, which may be of rather stiff paper.

It may be noted, in Fig. 2, that one of the ears 4^a is slotted, thereby enabling the 130

corresponding screw 5 to be slightly loosed to permit the shield 6 to be rotated about the other screw 5, thus giving access to the moistening roll and interior of the water-
5 font for the purpose of cleansing the same.

The foregoing detailed description has been given for clearness of understanding only, and no unnecessary limitations should be understood therefrom, but the appended 10 claims should be construed as broadly as permissible in view of the prior art.

What I regard as new and desire to secure by Letters Patent, is:—

1. In a machine of the character set forth, 15 the combination of a water-font, a pair of aligned, spaced moistening-rolls mounted therein, a pair of spaced guide-shields mounted on said font and provided with longitudinal slots above the moistening rolls, 20 a pair of presser-rolls mounted on said guide-shields and depending through said slots, and a seal-holder disposed at one side of said font.

2. In a machine of the character set forth, 25 the combination of a water-font, a moistening-roll-device journaled therein, a pair of guide-shields mounted on said font and separated by an upwardly open space, and a pair of presser-rolls mounted on said 30 guide-shields and depending through slots therein and co-acting with the moistening-roll-device.

3. In a machine of the character set forth, 35 the combination of a water-font, a moistening-roll device journaled therein, a pair of guide-shields mounted on the ends of said font and separated by an upwardly open space, each guide-shield comprising an angular member having a vertical arm mounted 40 on the end-portion of the font and a

plate projecting over the font and provided at its inner end with an upturned flange affording a bearing, said plate having also a longitudinal slot and a bearing at the outer end of said slot, and a presser-roll depending through each slot and co-acting with the moistening-roll device, each presser roll having journals loosely supported in said bearings to permit vertical movement of the presser-roll. 45

4. In a machine of the character set forth, the combination of a water-font, a moistening-roll device journaled therein, a guide-shield mounted on each end of said font, 50 each guide-shield being connected with an end of the font by a pivot disposed at one side of and extending parallel with the axis of the moistening-roll device, whereby the guide-shield may be swung on an axis parallel with the axis of the font to uncover 55 the moistening-roll device, and a presser-roll mounted on each guide-shield and depending through a slot therein and co-acting with the moistening-roll device. 60

5. In a machine of the character set forth, 65 the combination of a water-font provided with supporting standards, a moistening-roll device journaled in said water-font, presser devices co-acting with said moistening-roll device, said presser devices being 70 separated by an upwardly open space, and a seal receptacle disposed at one side of said water-font and having an inclined apron provided with a hook engaging the upper edge of one side of the water-font, the central portion of said apron being struck 75 downwardly and serving as a brace engaging the side of the water-font.

JOHN BERG.
